UNITED STATES PATENT OFFICE.

JAMES M. COLEMAN, OF MONTREAL, QUEBEC, CANADA.

REFRIGERATOR CAR.

1,402,571.

Specification of Letters Patent.

Patented Jan. 3, 1922.

Application filed October 20, 1920. Serial No. 418,188.

To all whom it may concern:

Be it known that I, JAMES M. COLEMAN, a citizen of the United States, residing at Montreal, in the Province of Quebec and 5 Dominion of Canada, have invented new and useful Improvements in a Refrigerator Car, of which the following is a full, clear, concise, and exact description, reference being had to the accompanying drawing, 10 forming a part of this specification.

My invention relates to freight car construction and more particularly to a ventilating system which will allow circulation for heating and cooling.

15 One of the objects of my invention is to provide an improved false floor construction, which can be easily gotten out of the way for the purpose of cleaning the car floor.

20 A further object of my invention is to provide a ventilated floor construction which will be durable and efficient in use, and simple in construction.

25 Further objects will appear from the detailed description to follow and from the appended claims.

In the drawings in which an embodiment of my invention is illustrated:

Fig. 1 is a horizontal section of a refrigerator car;

Fig. 2 is a vertical longitudinal section of the car;

Fig. 3 is a perspective view, showing the manner in which the false floor is folded;

35 Fig. 4 is a detail of the hinge connection;

Fig. 5 is a section on the line 5—5 of Fig. 4;

Fig. 6 is a detail view showing a hinge connection between the floor sections; and

40 Fig. 7 is a section on the line 7—7 of Fig. 6;

The refrigerator car construction shown in the drawings comprises in a general way the car proper, comprising the main floor 10, the side walls 11, the roof 12, the end compartment 13 for the ice 14 or heating device 15, and the double end wall 16, which provides a passage for circulation at the end of the car, and in addition to the car proper, a removable false floor 17 is spaced from the main floor 10, to provide a circulation passage, so that if, for instance, the car is being used in the winter, and the heating device 15 is used, the air can circulate, as indicated by the arrow A upwardly from the heating medium 15, along under the roof

12 and above the contents of the car, down through the double partition 16, and thence along between the false floor 17 and the main floor 10 to keep the contents of the car 60 from freezing.

The false floor 17 is made in six sections, indicated at 18, 19, 20, 21, 22 and 23. These sections are rectangular in plan, section 18 having its corners at 24, 25, 26 and 27 (Fig. 65 1), section 19 having its corners at 25, 26, 27 and 28, and section 20 having its corners at 27, 28, 29 and 30.

These three sections 18, 19 and 20 cover one-half of the car floor, on one side of the 70 longitudinal central line of the car floor and the sections which cover the other half of the floor 21, 22 and 23 are identical in construction with the sections 18, 19 and 20 respectively. In Fig. 1 the sections 21 and 75 22 are shown swung up into a vertical position.

In order to swing the false floor 17 up out of the way to get at the main floor 10 for cleaning purposes or for sweeping out the 80 car, the false floor sections 18, 20, 21 and 23 are hinged at their outside edges to the sides of the car so that these sections can be swung up against the side of the car, and the sections 19 and 22 are hingededly connected 85 to the sections 18 and 21 respectively (Fig. 3) so that after section 18 is thrown up against the side of the car, section 19 can be swung up against section 18.

It will be noted that the short sections 19 90 and 22 are located opposite the centrally located doors 31 of the car. This accomplishes two purposes. First, it facilitates removing the contents of the car, and second, it enables this section to be folded out of the 95 way of the door, so that one can easily get into and out of the car after the false floor is folded up out of the way.

The false floor sections are similar in construction, comprising a plurality of longitudinally extending stringers 32, which rest on the main floor 10, when the false floor is in use, and a plurality of cross pieces 33 which are secured to the stringers 32. The cross pieces 33 are spaced from the 100 main floor 10 because of the longitudinally extending stringers 32, so that free ventilating passages are provided from one end of the car to the other, underneath the cross pieces 33 between the stringers 32. The cross 105 pieces 33 are spaced from each other to permit the circulating air to pass up between 110

these cross pieces and keep the contents of the car at the desired temperature.

Any suitable hinge connection may be provided for the false floor section, one form of hinge connection between the floor section 18 and the side of the car being shown in Figs. 4 and 5, and one form of hinge connection between the false floor sections 19 and 20 being shown in Figs. 6 and 7.

10 Referring in detail to the hinge connection between the section 18 and the side of the car 11, showing Figs. 4 and 5, this comprises a screw-eye 34, screwed into the side of the car 11, and an eye-plate 35, secured 15 to the false floor section 18, and pivotally connected with the screw-eye 34. This construction permits the floor-section 18 to be thrown up against the side of the car as indicated in Fig. 3.

20 The hinge connection between the false floor section 18 and the short false floor section 19, shown in Figs. 6 and 7, is such that the short floor section 19 can be swung in either direction about the adjacent edge 25 of the longer floor section 18, for a purpose hereinafter discussed. This hinge connection comprises a pair of eye-bolts 36 secured to the floor sections 18 and 19 respectively, and a short chain 37 connecting the 30 two eye-bolts 36.

As many of these connections as are necessary are provided for connecting the floor sections 18 and 19, two such connections being shown in the drawings as indicated at 35 38 and 39 in Fig. 1. Also as many points of connection are provided between the floor section 18 and the side of the car 11, as may be necessary, three being shown in the drawings as indicated at 40, 41 and 42.

40 As indicated above the short false floor section 19 is connected to the larger false floor section 18 in such a way that it can be swung in either direction about the edge of the section 18, the chain 37, as shown in Fig. 7, 45 being made somewhat slack to permit this movement. This is desirable because when removing the contents of the car, it is desirable to swing this section in one direction, and in folding up the sections against the 50 side of the car after the contents of the car have been removed, it is desirable to swing this section in the other direction. The advantage of being able to swing the short section 19 up out of the way in cleaning out 55 the car is that if the contents of the car are such that they have to be removed by a scoop shovel, it is desirable to use the main floor 10 as the scooping floor, rather than the false floor 17. By having the section 19 60 hingedly connected with the section 18, as soon as the section 19 is cleared off in unloading the car, this section can be swung up to permit access to a part of the main floor 10 and the contents of the car can be

raked down onto this bare spot on the main 65 floor 10, and this bare spot can be used as a scooping floor. When the other short false floor section 22 is cleared off it also can be swung up out of the way and additional scooping floor space gained. After the section 18 has been cleared off, the sections 18 70 and 19 can be gotten out of the way by swinging the section 18 up against the side of the car, and then swinging the short section 19 up against the section 18. It will 75 be noted that this latter movement of the short section 19 requires a movement in a direction opposite to that which was required in swinging it up out of the way when the false floor section 18 is in a horizontal position. As previously stated, the chain connection 37 permits this movement of the section 19 in either direction.

The manner in which the floor is used has been outlined in connection with the 85 description of the construction. After the contents of the car have been removed, the floor sections can all be swung up flat against the side of car, so that the main floor 10 90 is exposed and accessible for cleaning.

90 While I have shown one embodiment of my invention, it may be embodied in other forms, covered and defined by the appended claims.

Having thus described my invention, what 95 I claim as new and desire to secure by Letters Patent of the United States is:

1. A freight car construction comprising a car having a main floor and side walls, and a false floor above and spaced from 100 said main floor to provide a ventilating passage between said floors, said false floor comprising a first section foldable to swing about a horizontal axis against one of the side walls of the car, and a second section 105 hinged to said first section to swing about a vertical axis after said first section has been swung up against the side wall to a position adjacent and parallel to said first section.

110 2. A freight car construction comprising a car having a main floor, side walls and a side door-way, and a false floor above said main floor and spaced therefrom to provide a ventilating passage between said floors, 115 said false floor comprising a first section foldable to swing about a horizontal axis against one of the side walls of the car, and a second section opposite said door-way and hinged to said first section to swing 120 about a vertical axis after said first section has been swung up against the side walls to a position adjacent and parallel to said first section.

In witness whereof, I have hereunto subscribed my name.

JAMES M. COLEMAN.
